UNITED STATES PATENT OFFICE.

CHARLES H. SAPPER, OF NORFOLK, VIRGINIA.

CHUCK OR VISE.

1,205,795.

Specification of Letters Patent. Patented Nov. 21, 1916.

Application filed December 8, 1915. Serial No. 65,813.

To all whom it may concern:

Be it known that I, CHARLES H. SAPPER, a citizen of the United States, residing at Norfolk, in the county of Norfolk and State 5 of Virginia, have invented new and useful Improvements in Chucks or Vises, of which the following is a specification.

This invention relates to improvements in chucks or vises such as are commonly 10 used on planers, milling machines, shapers and other like machines, the object of the invention being to provide an improved chuck or vise which embodies in its construction jaw plates by means of which the 15 work may be forced downwardly as well as sidewise.

The invention consists in the construction, combination and arrangement of devices hereinafter described and claimed. 20 In the accompanying drawings, Figure 1 is a side elevation of a chuck or vise constructed and arranged in accordance with my invention. Fig. 2 is a plan of the same. Fig. 3 is a detail sectional view on a larger 25 scale and on the plane indicated by the line *a—a* of Fig. 2. Figs. 4—5 are detail views.

The chuck body or vise body 1 is mounted on a degree base 2 for pivotal movement and comprises a pair of arms 3 which are 30 connected together at one end by a fixed jaw 4 and at the other end by a bearing 5. A sliding jaw 6 is mounted on the arms 3 for movement toward and from the fixed jaw; the gib plates of the sliding jaw being indicated at 7. A screw 8 for operating the sliding jaw has a step bearing in the fixed jaw and is also swivelly mounted as at 9 in the bearing 5. A set screw 10 is mounted as at 11 and is arranged for engagement with the 35 degree base to hold the chuck or vise at any desired angular adjustment.

In accordance with my invention each jaw is provided on its inner side with upper and lower inclined plane faces 12—13 which are 40 parallel and is also provided with a flange or shoulder 14 which is horizontal and which together with the inclined plane faces extend from end to end of the jaw. The inclined plane faces of the jaws converge upwardly as shown. 45 Each jaw is also provided on its inner side with a groove 15 which extends from end to end thereof, which is rectangular in cross section and is at right angles to the inclined plane face 13. Each jaw is also provided on 50 its inner side with inclined guide bores 16 which extend up through the flange or

shoulder 14 and are parallel with the inclined plane faces 12—13.

In the center of each jaw is a vertical bore 17 the upper end of which is threaded as at 18 and the lower end of which communicates with a horizontally arranged recess 19 which opens at the inclined plane face 13 and is intersected by the groove 15.

In connection with each jaw of the chuck or vise I provide a steel key plate 20 the inner side 21 of which is plane and perfectly vertical and the outer side of which is provided with upper and lower inclined plane faces 22—23 which are exactly parallel with and engage the inclined plane faces 12—13 of the jaw. Each key plate also has a horizontal flange or offset 24 between its inclined plane faces and which is movable toward or from the offset flange of the jaw 75 or plane 14, the key plates being vertically movable on the jaws and being in effect double wedge shaped as shown. When the key plates are moved downwardly on the jaws the space between them is increased and 80 when they are moved upwardly the space between them is diminished as will be understood. The upper portion of each key plate is provided with inclined guide bores 85 which register and align with the guide bores 16 of the jaw and guide pins 26 are arranged in said guide bores and serve to connect the key plates to the jaws as will be understood. Each key plate also has a groove 27 in its outer side which corresponds with the groove 15 of the jaw and extends from end to end of key plate and at the center of each key plate is a substantially semi-circular recess 28 which intersects the groove 27.

A link bar 29 connects each key plate to one of the jaws and is arranged in the grooves 15 and 27. Each link bar is coextensive in length with the jaws and key plate and is Z-shaped cross sectionally as 100 shown, and passes through a similarly shaped opening 30 in the center of the fulcrum head 31 of a lever bar 32. Said fulcrum heads are seated in the recesses 28 and said lever bars extend through the recesses 105 19 and are arranged at the lower ends of the vertical bores 17 and are each provided with a threaded opening 33. Set screws 34 secure the lever bars to the link bars and are arranged with their heads in clearance 110 openings 35 with which the key plates are provided. Operating screws 36 are ar-

ranged in the bores 17, bear at their lower ends at the bottoms of said bores and also of the recesses 19, engage the threaded openings 33 of the lever bars 32 and have their upper ends arranged in the central bores of sleeve plugs 37 which are screwed into the threaded upper ends of the bores 17. Coiled springs 38 are arranged in the said bores and around said operating screws and bear 10 between the lower ends of the sleeve plugs and the upper side of the levers 32.

The springs exert their tension to normally depress the outer ends of the lever bars and cause the latter to slightly turn the link 15 bars so that the link bars serve to normally raise the key plate. The tension of the springs is such that while they normally hold the key plate raised they enable the key plates to be forced downwardly if sufficient 20 pressure be applied, as when work is being held tightly between the key plates. When, for set gage work it may be desired to set one or both of the key plates in its lowered position this can be accomplished by turning 25 the screws 36 in the required direction to lift the free ends of the lever bars 32. In practice the bores of the sleeve plugs are of somewhat greater diameter than the screws 28 to permit the required slight angular movement of said screws with the lever 30 bars. Hence the chuck or device can be used or converted into a common or regular chuck or vise at will. At all adjustments of the key plate their opposing faces are perfectly 35 parallel.

While I have herein shown and described a preferred form of my invention I would have it understood that changes may be made in the form, proportion and construction of the several parts without departing 40 from the spirit of the invention as defined by the appended claims.

Having thus described my invention, I claim:—

45 1. In a device of the class described a pair of jaws arranged for movement toward and from each other and provided with inclined opposing upwardly converging faces and key plates having inclined faces corresponding with and engaging those of the jaws and having vertical parallel opposing faces, and

means to raise and lower the key plates, on the jaws.

2. In a device of the class described a jaw having a plane inclined face, a key plate 55 having a vertical work engaging face and an inclined face engaging that of the jaw, a link bar mounted for angular movement in grooves in the opposing sides of the jaw and key plate, a lever bar connected to said link bar and means to operate said lever bar whereby to raise and lower the said key plate.

3. In a device of the class described a jaw having a plane inclined face a key plate 65 having a vertical work engaging face and an inclined face engaging that of the jaw, a link bar mounted for angular movement in grooves in the opposing sides of the jaw and key plate, a lever bar connected to said 70 link bar, a spring exerting its tension on the lever bar to normally cause said lever bar and link bar to raise the key plate and a screw to move the lever bar against the tension of the spring and thereby lower the key 75 plate.

4. In a device of the class described a jaw having a plane inclined face a key plate having a vertical work engaging face and an inclined face engaging that of the jaw, a 80 link bar mounted for angular movement in grooves in the opposing sides of the jaw and key plate, a lever bar connected to said link bar, a spring exerting its tension on the lever bar to normally cause said lever bar 85 and link bar to raise the key plate and a screw to move the lever bar against the tension of the spring and thereby lower the key plate, said jaw having a recess in which the lever bar operates and also having a bore 90 communicating with said recess and in which the spring and the adjusting screw are arranged, and a plug sleeve in the upper end of said bore and forming a guide for the adjusting screw.

95 In testimony whereof I affix my signature in presence of two witnesses.

CHARLES H. SAPPER.
